(57) **CLAIM**

We claim the ornamental design for a plug-in load control device, as shown and described.

DESCRIPTION

FIG. 1 is a first perspective view of a plug-in load control device according to a first embodiment of our new design. FIG. 2 is a second perspective view of the embodiment depicted in FIG. 1.

FIG. 3 is a front view of the embodiment depicted in FIG. 1.

FIG. 4 is a left side view of the embodiment depicted in FIG. 1.

FIG. 5 is a right side view of the embodiment depicted in FIG. 1.

FIG. 6 is a top view of the embodiment depicted in FIG. 1.

FIG. 7 is a bottom view of the embodiment depicted in FIG. 1.

FIG. 8 is a first perspective view of a plug-in load control device according to a second embodiment of our new design. FIG. 9 is a second perspective view of the embodiment depicted in FIG. 8; and,

FIG. 10 is a front view of the embodiment depicted in FIG. 8, the left side, right side, top, and bottom views, respectively, of the second embodiment depicted in FIG. 8 being identical to the left side, right side, top, and bottom views of the first embodiment depicted in FIG. 1.

The rear views form no part of the design and are omitted. The portions of the drawings appearing in broken line are for environment only and do not form a part of the claimed design.
